UNITED STATES PATENT OFFICE.

WILLIAM O. WISNER, OF HOOPER, NEBRASKA, ASSIGNOR OF ONE-THIRD TO
HIRAM A. STURGES, OF OMAHA, NEBRASKA.

AUTOMATIC ROADWAY-GUARD.

SPECIFICATION forming part of Letters Patent No. 606,614, dated June 28, 1898.

Application filed March 5, 1897. Serial No. 626,133. (No model.)

To all whom it may concern:

Be it known that I, WILLIAM O. WISNER, a citizen of the United States of America, residing at Hooper, in the county of Dodge and State of Nebraska, have invented certain new and useful Improvements in Automatic Roadway-Guards and Signals for Crossings; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to an improved roadway-guard designed for use at railway-crossings, drawbridges, and similar places; and it has for its object to provide a simple guard which will be operated by the passing train or other vehicle both to extend the guard before the vehicle reaches the crossing to be protected and to retract it after the train has passed the protected crossing.

The invention consists in a certain novel combination and arrangement of parts, as hereinafter described, and particularly pointed out in the claims appended.

In the drawings, Figure 1 is a perspective view showing the guard extended. Fig. 2 is a side-elevation showing the guard folded, and Fig. 3 is a detail view.

Referring to the various parts by numerals, 1 designates a suitable support, which is to be located in such a position that the extended 35 guard will reach across the street to be protected. Within this support, at its upper end, is a rigid horizontal bar 2, upon which is pivoted the upper end of a lever 3, which lever forms one part of the inner section of a lazy-tongs 4. The other part, or lever 3', of this inner section of the lazy-tongs is pivoted on a horizontal rod 5, which is supported at its ends in vertical guides 6, secured to the support, which guides are open at their upper 45 ends. This rod is held in these guides against lateral movement, but is adapted to move vertically therein. Pivoted on a horizontal pivot located near the bottom of the guides 6 is a bell-crank lever 7, to one of whose arms a link 50 8 is connected. The other end of this link is connected to one of the inner levers of the lazy-

tongs. Connected to the other arm of lever 7 is the upper end of a pitman 9, whose lower end is connected to a crank 10 of a horizontal crank-shaft 11, which is supported in suitable bearings, its inner end being mounted in the main support 1. Secured to this shaft at a suitable point is a crank 12, which at its outer end is formed with the broad curved surface 13. Secured at each end of this curved surface is 60 an operating rope or wire, each of said ropes or wires being so secured that when one is drawn outward to operate the gate in one direction the other one will be wound upon the curved portion of the crank. These wires 65 extend to any desired distance from the shaft 11, one extending in one direction and one in the opposite direction, the wire 14 being designed to open or extend the guard, while 14' is designed to fold it. To the outer ends of 70 these wires levers 15 are secured, the free ends of said levers extending into the path of the passing trains and being adapted to be engaged by those trains going in a certain direction and to thereby operate the guard.

It is obvious that by duplicating the operating levers and crank and their connecting-wires the gate may be extended by trains approaching from either direction and folded by them after they have passed the protected 75 crossing.

It will be readily understood that the support may be so constructed that the guard will be under cover when folded and that other means of operating the rock-shaft may 85 be employed.

It will be observed that by employing the bell-crank 7 and pivoting it upon the frame at a point below the lazy-tongs I am enabled to use an operating-link 8, lying in a substantially horizontal position and connected to one of the inner levers of the lazy-tongs beyond the pivotal point of the two levers comprising the inner section thereof. The advantage of this construction is that a direct 90 push-and-pull action is obtained, thereby reducing the strain and operating power to a minimum. This construction also enables the necessary movement of the lazy-tongs to be obtained with a minimum movement on 95 the part of the crank-shaft below, it being evident that by simply lengthening the bell-

crank arms any desired length of stroke may be obtained.

It will be observed that the advantage of leaving the upper end of the guideways 6 open the lazy-tongs can be readily removed for repair, it being simply necessary to remove shaft 2 and disconnect link 8, whereupon the lazy-tongs may be lifted out of the frame.

10 It will be observed that the lazy-tongs remains folded and lies within the frame until the approach of a train, whereupon it is extended across the roadway parallel with the track and remains there until the train has 15 passed, whereupon it is again drawn in or folded. It will therefore be observed that the lazy-tongs remains in a folded position the greater part of the time.

Having thus fully described my invention, 20 what I claim, and desire to secure by Letters Patent, is—

1. In an automatic railway-guard, the combination of a support, upright guideways 6 thereon, said guideways being open at their 25 upper ends, a lazy-tongs mounted in said support, the upper end of one of the levers forming the inner section of said lazy-tongs being pivotally secured to said support, a cross-bar carried by the inner, lower end of 30 the other lever of the said inner section, said cross-bar being vertically movable in said guideways, a bell-crank lever 7 pivoted in the support below the lazy-tongs, a substantially horizontal link connecting the upward-extending arm of the bell-crank to one of the 35 levers of said inner section of the lazy-tongs, and means connected to the other arm of said bell-crank lever and adapted to be operated

by the passing vehicle whereby the lazy-tongs will be extended during the passage of the 40 vehicle and be folded when said vehicle has passed by the guard, substantially as described.

2. In an automatic railway-guard, the combination of a support, provided with upright 45 guideways open at their upper ends, a lazy-tongs mounted in said support, the upper end of one of the levers comprising the inner section of said lazy-tongs being pivoted to said support, a cross-bar carried by the inner, 50 lower end of the other lever of said inner section, said cross-bar being vertically movable in the guideways and held against lateral movement therein, a substantially horizontal link connected to one of the levers of the inner 55 section of the lazy-tongs beyond their common pivot, a bell-crank lever mounted on a support below the lazy-tongs, one arm of said lever being connected to the end of said link, a crank-shaft below the bell-crank lever, a pitman connected to the other arm of said bell-crank and also to the crank-arm on said crank-shaft, another crank-arm on said shaft, and means connected to this latter crank-arm adapted to be operated by the 60 passing vehicle, whereby the guard will be extended during the passage of the vehicle and folded when said vehicle has passed by the guard, substantially as described.

In testimony whereof I affix my signature 70 in presence of two witnesses.

WILLIAM O. WISNER.
